UNITED STATES PATENT OFFICE.

LESTER STEWART BARR, OF WASHINGTON, DISTRICT OF COLUMBIA.

DETECTOR.

1,122,358.

Specification of Letters Patent. Patented Dec. 29, 1914.

Application filed September 10, 1913. Serial No. 789,082.

To all whom it may concern:

Be it known that I, LESTER STEWART BARR, a citizen of the United States, residing at Washington, in the District of Columbia, have invented a new and useful Detector, of which the following is a specification.

My invention relates to improvements in apparatus for wireless or Hertzian wave telegraphy, and more particularly to the class of instruments known as detectors.

10 In general, it is the function of the detector to so modify or transform the currents set up in the receiving circuit as to render them capable of acting upon the receiver proper to produce sensible signals. Of the various types of apparatus which have been employed for this purpose, the type known as the crystal detector has proved the most satisfactory for general use, and it is my object to improve the mechanical structure of the crystal detector so as to free it from certain well recognized mechanical faults which have hitherto operated to impair the inherent virtues of the type.

25 In order that the invention may be more readily understood I will briefly outline the electrical principles which underlie the action of this type of detector, and enumerate the essential mechanical features of a practical embodiment of the apparatus.

30 It has been found that a small surface contact between a metallic electrode and certain crystalline mineral substances, for instance, galena, silicon, etc., has the property of exerting a rectifying action on high frequency electrical currents. This property of the contact is somewhat elusive, almost disappearing at times without apparent cause and varying in efficiency at different

40 points of the surface and at different times. The pressure of contact is found to influence materially the results obtained, but this also is according to no established principle, arbitrarily varying between moderate limits.

45 In general therefore the essentials of a detector of this type are:—A crystal mounting providing electrical connection between the crystal and leading-in-wire. An electrode mounting and electrical connection.

50 Means for changing the point of contact between the electrode and crystal. Means for varying the pressure of contact.

It is my object to provide a simple and efficient device in which the above essentials

55 are present and in which especial advan-

tages relating to facility of adjustment are embodied.

With the above and other objects, which will appear as the description proceeds, in view, I have designed the form of detector described in the annexed specification and illustrated by the accompanying drawings, in which:—

Figure 1 is an elevation, partly in section of one embodiment of my invention, and Fig. 2 is a plan view of the same.

Like characters denote the same parts in each view.

(1) indicates the base block of the detector, conveniently formed as a rectangular plate of vulcanite. Let into the upper face of the base block so that their surfaces shall be flush with the same, are the metallic contact plates—(2) and (3) carrying respectively the binding posts—(4) and (5) for the leading-in and leading out conductors. The under face of the contact plate (2) is formed with a boss (6) which is drilled and tapped centrally to provide a securing means for the crystal cup (7), as shown by the broken away portion of Fig. 1. This cup is of generally cylindrical form and comprises an inner shell (8), preferably of steel, flanged over at the top to form a shoulder, and a sleeve of vulcanite (9) which surrounds the inner shell and is clamped between the shoulder thereof and the contact plate (2). The clamping is effected by means of a threaded stud (10) which is preferably formed integrally with the bottom of the inner steel shell (8) and takes into the threaded opening in the boss (6). The wall of the cup (7) is drilled and tapped near the bottom to receive a horizontal displacement screw (11) the function of which will appear later.

Mounted on the contact plate (3) is a metallic pillar (12), the pillar being secured to the plate and base-block by an integral threaded stud (13) which passes through a countersunk bore in the base block and receives a nut (14) which seats in the recess formed by the countersink. The upper end of the pillar is enlarged at (15) and bored horizontally to receive the needle arm (16) with a sliding fit. The arm (16) is secured in any adjusted position by a set screw (17) in the top of the pillar. The outer extremity of the needle arm is enlarged as at (18), the enlargement being drilled and tapped

- vertically to receive the vertically adjustable screw (19). In the lower end of the needle screw is mounted the steel needle (20) which forms the contact electrode of the detector.
- 5 As a precaution, the head of the needle screw may be formed of a separate disk of vulcanite or other insulating material, indicated at (21). In order that the needle screw may be held against accidental rotation, the end of the arm (16) may be split as far back as the enlargement (18), the split end being clamped into good frictional engagement with the needle screw by means of the small clamping screw (22).
- 10 15 The apparatus above described, having been properly assembled, the cup (7) is filled about two-thirds full with an electrically conductive fluid, preferably metallic mercury or quicksilver, indicated at (23), and a crystal of proper size, indicated at (24), is placed in the cup. In general, any crystalline mineral suitable for use in a detector will have a specific gravity less than that of the mercury, and the crystal will therefore float at the top of the cup. The needle screw will then be lowered until the contact point touches the surface of the crystal. The detector being properly connected into the receiving circuit the operator 20 25 will make use of his testing buzzer in a manner well understood in the art, and continue to lower the needle until an approximate adjustment is obtained, as indicated by the sound heard in the ear-phones. It will be 30 35 obvious that as the needle is lowered the crystal will displace more and more of the mercury and the pressure of the contact will gradually and uniformly increase. After an approximate adjustment has been obtained by lowering the needle screw, the displacement screw (11) may be brought into use to effect the final adjustment. By advancing this screw into or withdrawing it from the cup the level of the mercury therein may be changed by infinitesimal amounts, thus effecting a most delicate adjustment of the pressure of contact.
- 40 45 It may often happen that the particular point of the crystal on which the needle bears does not give satisfactory results, or that from use or other causes this particular contact has deteriorated. In either event it is only necessary to tap the crystal with the finger, thereby depressing it out of contact with the needle, and when the crystal is released and rises against the needle again there will be a new contact point with substantially the same pressure which was before found most advantageous. Any difference in pressure can only be due to slight differences in form and consequent displace-

ment of the submerged portion of the crystal. It will be apparent also that with great facility the whole surface of the crystal may be searched in order to locate the most advantageous contact, it being possible to try new contacts as fast as the finger can move to tap the crystal. The importance of being able to reach a new point with the least loss of time will be understood, when it is remembered that a contact may deteriorate so far as to become useless while the operator is taking a message.

It will also be noted that the effect of temperature changes upon the instrument is negligible, such changes giving only a minute difference of immersion of the crystal.

The electrical efficiency of this type of detector is very high, owing to the exceptionally good electrical connection furnished by the mercury. It will therefore be seen that I have provided a simple and efficient instrument in which the inherent simplicity of the crystal contact detector is conserved, and in which the necessary adjustments may be easily and quickly accomplished, and when once accomplished may be maintained.

While I have shown and described a specific embodiment of my invention, including numerous details and refinements of construction, it will be understood that this is purely illustrative and that the scope of my invention is to be determined only by the terms of the claims hereunto annexed.

What I claim is:—

1. In a crystal detector, a crystal mounting comprising a receptacle, a mercury pool within the receptacle, a crystal freely floating on the surface of the mercury and spaced from the walls of the receptacle, and a contact electrode supported to bear upon the exposed upper face of the crystal, whereby the crystal may be rotated within the mercury pool to bring any point of its surface in position to contact with the electrode.

2. In a crystal detector, a crystal mounting comprising a receptacle, a mercury pool within the receptacle, a displacement screw for varying the level of mercury within the receptacle, a crystal freely floating on the surface of the mercury and spaced from the walls of the receptacle, and a contact electrode supported to bear upon the exposed upper face of the crystal, whereby the crystal may be rotated within the mercury pool to bring any point of its surface in position to contact with the electrode.

LESTER STEWART BARR.
